AMPHIBIAN TOY DUCK

Thomas C. Martin, Cohasset, Mass.

Application July 7, 1949, Serial No. 103,440

4 Claims. (Cl. 46—92)

1

The present invention relates to a toy and in particular to an improvement in the toy shown in my copending application, Serial No. 750,259, filed May 24, 1947, and more particularly to certain constructional features relating to the article when produced as a plastic molded device in which the main structure of the article is molded in two parts and joined together on an axial seam symmetrical with a central longitudinal plane through the device itself.

The article of the present invention is a caricature of a duck in which the lower beak and eyes are balanced on a pivoting arm in the head section of the figure and produces when rocking forward and backwards on the base, an animation of the beak and the eyes which is particularly attractive.

The improvements in the present invention will be more readily appreciated and understood from a consideration of the specifications set forth below, describing an embodiment of the same when taken in connection with the drawings thereto, in which:

Figure 1 shows a side elevation of the toy with parts shown in fragmentary section.

Figure 2 shows a sectional view taken substantially on the line 2—2 of Figure 1.

Figure 3 shows a front elevation with parts shown in fragmentary section, and

Figure 4 shows a detail of construction as viewed looking at the front of the head piece with the beaks removed.

As indicated in the drawings, the article is molded in two half sections, 1 and 2, divided along the center line 3 in an interlocking lap joint 4 providing a smooth joining surface all around the periphery of the article.

The device which is a caricature of a duck is provided with rounded bottom surface 5, as viewed from the side (Figure 1), and a flat transverse line of contour 6, as indicated in Figure 3. The lower surface has therefore a contour similar to the shape of the rockers in a rocking chair and is arched in a smooth curve so that the toy will oscillate when placed on a wet surface and it will also oscillate when immersed in water. The joint at 3 around the contact of the base 7 is made water-tight by suitable cement, since each half of the toy is a shell with a hollow space within. The shell may be of suitable thickness, as for instance $\frac{1}{8}$ " or more in thickness and the whole thing may be molded of suitable plastic material, such as cellulose acetate or some other equivalent thermoplastic molding material. At the center of the base there projects at the inner side of each base wall a set of upright flanges 9

and 10 as well as a pin 11 substantially mid-way between the two flanges 9 and 10. These two flanges and pins all on both sides of each half of the duck, are designed to hold in place a metal weight 12, which may be of lead, iron or other suitable heavy metal. The weight 12 in assembly is first put in place in one half of the duck, and then when the two halves are put together in cementing, the weight fits in place on 5 the other half of the duck. At the top of the base element 7 is a short strip of heavier section 13 which joins the head section 14 with the base. Just behind this heavier coupling section is a slit 15 which communicates only with the head element. This head element 14 is not completely water-tight because of the slit opening 15 and also the forward opening or slot 16 through which the lower beak element 17 projects. Both lower beak element 17 and upper beak element 18 are 10 molded in two halves along a central plane coinciding substantially with the central plane in which the two halves of the duck are joined together. The beak 18 is so formed that it has a sharp or V-shaped top edge 19 while the beak 17 has a sharp or V edge 20. On one of the molded halves of the beak 18 is an inwardly extending 15 rectangular boss 21 which fits in a recess 22 of a shoulder flange 23 just behind the outer shell wall 24 behind the end of the upper beak 18 which fits into a triangular cavity 50, formed on the junction of the two halves of the head piece (Figure 4). The pin 25 projecting from the inner side of the wall of the head piece on one half as 20 shown in Figures 1 and 4, is aligned in the middle of the recess 22 so that the upper beak member 25 will rest snugly against the head with the back surface 26 of the beak resting against the flanged shoulder 23 and the square shaped projection 21 projecting through the slot or recess 22 with the pin 25 projecting into a hole at the center of the 25 projecting section 21.

A similar flange corresponding to the shoulder 23 is made in the other half of the head piece and this lays up against the edge of the shoulder 23 and against the flat end 26 of the beak. This 30 construction also provides a recess in the outer wall of the head piece in the region of the shoulder flange to accommodate the end of the beak which has a flat surface at the end and is arched at the lower surface of the beak with the two side edges coming to a vertex thus forming a sector approximately of a circle. This flat end section of the beak rests against the exposed forward surface of the shoulders 23 so that the upper beak in this fashion is held very strongly in the head 35 and cannot be readily knocked or broken off. It

is preferable to use cement to cement the beak in place which thereby effects a very rigid structure. Just below the point where the upper beak 18 is attached to the head section, is the rectangular opening 16 through which the lower beak 17 projects. One half of the lower beak 17 is formed as a part of the lever 27 by a connecting flange 28. The lever 27 is however symmetrically aligned with the center joining line of the two halves of the beak by extending the material of the lever over the same distance on the end of the half of the beak which is not directly joined to the lever. The lever is provided with a pin 29 which may be of metal, which pin projects through a hole in a slightly enlarged section of the lever. The lever 27 extends rearwardly into the head and at its end is terminated in a plate section 30 with two outwardly projecting pins 31 and 32. These pins are long enough to extend substantially to the walls 33 and 34 of the head section of the duck. This arrangement prevents a sidewise oscillation of the beak in its motion and also furnishes additional strength and steadiness in the construction of the beak. The pin 29 which is the pivoting pin sets in bearing elements 35 and 36 which are portions of the molded plastic projecting from the sides of the walls 33 and 34 respectively.

The eye structure is also supported by the lever 27. For this purpose the lever 27 has a wider rectangular section 37 formed as a part of the lever which section projects sidewise towards the side walls 33 and 34 and comes sufficiently close so that the two discs 38 and 39 may be attached to the side edges of the base 37 by suitable means, the means preferable in the present case being simply by snapping the discs over pins 40 and 41 projecting from the side edges of the plate 37 and engaging in snap fitting holes in the discs 38 and 39. Similarly the convex eye members 42 and 43 may be snapped into the centers of the disc by means of projecting pins 44 engaging in snap fitting holes at the center of the discs 38 and 39. The eyes may be suitably colored as desired.

The head section 14 on each side is provided with a window opening 45 over which a clear window may be inserted so that the eye discs will be visible from the outside. At the top of the head piece 14, a recess 46 is provided into which a cap 47, such as a sailor cap, may be inserted and cemented in place.

The construction which has been described provides a rigid toy construction which will withstand a great amount of rough use by children. The toy itself is well balanced both for use on a hard surface and for immersion in water. In use in water, the weight 12 which is placed at the lowest point of the base extending broadly across the width, provides a center of gravity which is sufficiently lower than the center of buoyancy, so that a substantial righting stability is obtained. In this construction the weight is made flat and hugs as nearly as possible the base, so that a small weight is sufficient for the purpose.

Since the beak projects forward of the duck, the general position of the weight 12 is slightly rearward of the center line of the duck to provide the proper balance. An additional feature of the toy is that when it is rocking, either on a

board or in water, the lower beak 17 has sufficient motion amplitude so that it will strike the breast of the duck and produce a noise comparable to the quacking of a duck.

Having now described my invention, I claim:

1. An amphibian toy of the type described simulating the caricature of a duck, comprising a thin walled shell formed with a rocking-chair like base and a head, said base and head being molded as integral halves joined substantially symmetrical therewith, means joining said base to effect a complete water tight seal around the whole joined area to render the toy buoyant, an upper and lower beak element attached to said head and projecting from the forward end thereof, said base having positioned at its lowest region a flat counter weight extending transversely across the base on the inner side and slightly rearward of a center line of the duck offsetting the forward projection of said beaks, whereby the toy will perform a rocking action on a solid surface and on water a pair of flanges projecting from the base at the sides and a pin element between said flanges and positioned above the same also projecting from the sides retaining said weight in place.

2. An amphibian toy of the type described simulating the caricature of a duck, comprising a thin walled shell formed with a rocking-chair like base and a head, said base and head being molded as integral halves joined substantially symmetrical therewith, means joining said base to effect a complete water tight seal around the whole joined area to render the toy buoyant, a beak comprising upper and lower members inserted at the forward portion of said head and a counter weight positioned at the lowest point of the base, said counter weight extending across the base and forward and rearward of the central section thereof and means fixing said counter weight in a stationary position whereby the toy will perform a rocking action on a solid surface and on water.

3. A toy as set forth in claim 2 having means for pivoting the lower member of said beak between the molded integral halves of said head, said lower beak having an sufficient swing when the toy is performing its rocking action, whereby it will periodically strike the base portion of said body and produce a sound.

4. An amphibian toy as set forth in claim 2 having a complete seal about the halves of the head except for a drain slot in said head at its lowest point at the rear thereof whereby any water which may enter the head will automatically drain off when the toy is in an erect position.
